UNITED STATES PATENT OFFICE.

JAMES W. ASHBAUGH, OF BREMEN, OHIO.

DESIGN FOR A GAS-STOVE.

46,796.

Specification for Design.

Patented Dec. 29, 1914.

Application filed June 30, 1914. Serial No. 848,312. Term of patent 7 years.

To all whom it may concern:

Be it known that I, JAMES W. ASHBAUGH, a citizen of the United States, residing at Bremen, Fairfield county, Ohio, have invented a new, original, and ornamental Design for Gas-Stoves, of which the following is a specification, reference being had to the accompanying drawing, forming part thereof.

The figure is a front view of a gas stove, showing my new design.

I claim:

The ornamental design for a gas stove, as shown.

JAMES W. ASHBAUGH.

Witnesses:

J. F. THOMPSON,
J. H. LEONARD.
